UNITED STATES PATENT OFFICE.

HANS O. JOHNSON, OF SACRAMENTO, CALIFORNIA.

SAFETY APPLIANCE FOR VEHICLES.

1,129,985.

Specification of Letters Patent. Patented Mar. 2, 1915.

Application filed May 21, 1914. Serial No. 839,986.

To all whom it may concern:

Be it known that I, HANS O. JOHNSON, a citizen of the United States, residing at Sacramento, in the county of Sacramento and State of California, have invented certain new and useful Improvements in Safety Appliances for Vehicles; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in safety appliances for vehicles and is particularly adapted to street cars and automobiles.

The object of the invention is to produce a device which may be readily attached to the front of a vehicle and when not in use, folded up out of the way.

A further object of the invention is to produce a simple and inexpensive device and yet one which will be exceedingly effective for the purposes for which it is designed.

These objects I accomplish by means of such structure and relative arrangement of the parts as will fully appear by a perusal of the following specification and claims.

On the drawings, similar characters of reference indicate corresponding parts in the several views.

Figure 1 is a side elevation of the appliance. Fig. 2 is a side elevation showing the appliance in folded position. Fig. 3 is a top plan view of the same showing the appliance in extended position. Fig. 4 is a sectional view, partly broken out, of the roller. Fig. 5 is an enlarged end view of the supporting brackets showing the relative positions of the parts supported thereby.

Referring now more particularly to the characters of reference on the drawings, the numeral 1 designates the frame or other convenient part of the vehicle to which my improved appliance may be attached.

The numeral 2 designates a bracket and the numeral 3 the clamps for fastening the bracket 2 to the frame 1. Slidable upon the bracket 2 is a member 4 provided with a set screw 5 for holding the same in any desired position.

Adjustable in the members 4 are rods 6 which are held in position by set screws 7. Fastened to each of the rods 6 is a member 8 provided with a lug 10. A lug 9 is provided upon one of the said members 8. The lugs 10 provide bearings for the shaft 11 upon which is mounted a roller 12 which carries a fabric 13. To the members 8 are fastened arms 14 pivotally mounted on pins 15 and connected to the said arms 14 are arms 16 pivotally mounted upon pins 15a. Near the ends of each of the arms 16 a cross member 17 is pivotally mounted upon pins 18, the fabric 13 being connected to the said member 17.

On the arm 16 I provide a shoulder 19 which, when the arm is in extended position, as shown in Fig. 3, will come into contact with a pin 20 integral with the arm 14. I provide on the member 8 a shoulder 21 which, when the arm 14 is extended as shown in Fig. 3, will come into contact with a pin 22 integral with the member 8, thus forming a stop for said arm.

A spring 23 is mounted on the pin 15, one end of which is fastened to the member 8 and the other end to the arm 14, the action of which tends to throw the arm 14 outwardly, as shown in Fig. 3, when the ratchet 24 is released by a pawl 25. At the same time a spring 26 will act to throw the arm 16 outwardly until the shoulder 19 has come into contact with the pin 20, as shown in Fig. 3.

Fastened to the shaft 11 of the roller 12 is a ratchet 24 in engagement with which is a pawl 25 pivotally mounted on a pin 27 provided with a spring 28 which holds the pawl in contact with the ratchet 24. To release the ratchet 24 from said pawl 25, I have provided integral with the pawl 25 a pin 29 working in a slot 29a, under which pin 29 projects an arm 30 on the end of a shaft 31 pivoted on the lug 9 of the member 8. On the opposite end of the shaft 31 is an arm 32 to which is secured any suitable connection 33 running to a lever 34 mounted on the dashboard 35 of the vehicle.

To extend the appliance, pressure is exerted upon the lever 34 thereby releasing the pawl 25 from the ratchet 24 so that each of the springs 23 and 26 will throw the respective arms 14 and 16 outwardly as shown. This action of the springs is made possible by reason of the fact that in rolling up the fabric 13 the tension of each of the said

springs is increased to the maximum point since the turning in of the arms upon the pins 15^a and 18 acts to wind up the springs 23 and 26. With the outward movement of 5 the arms 14 and 16, the cross member 17, which is pivoted to the arms 16, will likewise be carried outward, thus unrolling the fabric 13. The object of this is to overcome any tendency of the arms to double up when 10 the member 17 comes into contact with a heavy body.

To fold the appliance after it has been extended, a crank or key is attached to the square end 36 of the shaft 11 and rotated 15 until the appliance is in a position as shown in Fig. 2. The spring 37 is provided to work against the rotation of the roller 12, thereby holding the fabric 13 always tight and aiding in re-rolling the same.

20 The device, as will be noted, is especially adapted for use on the front end of automobiles, street cars or in fact any other form of vehicle found desirable. It is not continuously extended as are the ordinary fenders or bumpers now commonly used on vehicles, but is normally rolled up in closed position out of the way and is not unsightly nor particularly in the way when not in use. When the operator of the vehicle, however, 25 sees that an accident or collision with any person or other object is unavoidable, he can instantly throw the safety appliance into operative position by merely stepping on or touching the control lever 34. This 30 releases the parts and throws the arms 14 and 16 to extended position, carrying with them the bar 17 and unrolling the fabric 13. By reason of the fact that the device is not continuously extended, it can under these 35 last named conditions be extended to a point immediately adjacent the ground, and for that reason the structure will be positive in its action in engaging the person or object 40 described, which person or object will drop onto the fabric 13 instead of being run down and over by the wheels of the vehicle. Then, when the necessity of the use of the structure 45 is passed, the arms 14 and 16 are folded slightly inwardly to allow of the retracting

operation for the fabric to be started, and 50 then the entire device is folded up in normal closed position again, as described.

From the foregoing description it will readily be seen that I have produced such a device as substantially fulfills the objects of 55 the invention as set forth herein.

While this specification sets forth in detail the present and preferred construction of the device, still, in practice, such deviations from such detail may be resorted to as 60 do not form a departure from the spirit of the invention.

Having thus described my invention what I claim as new and useful and desire to secure by Letters Patent is:—

65 1. A device of the character described comprising the combination with a vehicle, of brackets mounted thereon, a roller rotatably mounted in said brackets, means for locking said roller against rotation, spring 70 pressed arms pivotally mounted on said brackets and capable of extending outwardly therefrom and being folded inwardly in the same plane, a fabric mounted on said roller and secured to said arms and means for releasing said locking means, as described.

75 2. A device of the character described comprising the combination with a vehicle, of brackets mounted thereon, a roller rotatably mounted in said brackets, means for 80 locking said roller against rotation, a pair of spring pressed arms pivotally mounted on said brackets, another pair of spring pressed arms pivotally mounted on the outer 85 ends of said first named arms, all of said arms being adapted to be folded inwardly in the same plane, a cross bar pivotally connected to the outer end of said second named arms, a fabric mounted on said roller and connected with said cross bars, and means 90 for releasing said locking means, as described.

95 In testimony whereof I affix my signature in presence of two witnesses.

HANS O. JOHNSON.
